UNITED STATES PATENT OFFICE.

HENRY L. JESSEN, OF WATSONVILLE, CALIFORNIA.

CARBURETER FOR EXPLOSIVE-ENGINES.

SPECIFICATION forming part of Letters Patent No. 657,738, dated September 11, 1900.

Application filed November 15, 1899. Serial No. 737,017. (No model.)

To all whom it may concern:

Be it known that I, HENRY L. JESSEN, a citizen of the United States, residing at Watsonville, county of Santa Cruz, State of California, have invented an Improvement in Explosive-Engines and Generators; and I hereby declare the following to be a full, clear, and exact description of the same.

My invention relates to improvements in explosive-engines and generators by which the gas or vapor used in such engines is produced.

The object of my invention is particularly to provide for a constant and complete vaporization of a hydrocarbon liquid, a mixture of air with the vapor thus produced to make it explosive, and a means for regulating the flow by which it is supplied only when the engine is in operation.

My invention also comprises an igniter and details of construction, which will be more fully explained by reference to the accompanying drawings, in which—

Figure 1 is a sectional elevation of the generator supply-tank, showing an end view of the cylinder and its connection with the generator. Fig. 2 is a sectional view showing the inlet-valve and igniting device. Fig. 3 is a perspective view of the igniter. Fig. 4 shows the means for discharging the residue from the generator. Fig. 5 is an enlarged sectional view of the hydrocarbon-liquid inlet.

As shown in my present illustration, and which is the preferred construction, A is a horizontally-disposed casing, and connected therewith is a pipe 2, by which exhaust products from the engine-cylinder are discharged into the casing. 3 is a discharge-pipe from the casing, through which these products of combustion are finally disposed of.

Within the casing A is a horizontally-disposed revoluble cylinder 4, supported by hollow shafts, which are turnable in suitable bearings at each end of the cylinder. One of these shafts 5 serves as an inlet for a hydrocarbon liquid, which liquid is passed slowly through the cylinder by means of spirally-disposed interior flanges 6, and as the outside of this cylinder is exposed to the action of the hot exhaust from the engine the heat serves to vaporize or produce a gas from the liquid as it passes through the cylinder. This

gas is in turn withdrawn by the movement of the piston in the engine-cylinder 7, which under proper conditions draws the gas and a mixture of air sufficient to make it explosive through an inlet-valve 8, which connects by means of a pipe 9 with the cylindrical shaft 10 at the discharge end of the cylinder 4.

A certain amount of air is admitted into the generator through the outer end of the hollow shaft 5, which has an opening controlled by a spring-pressed valve 11 for that purpose, and the liquid from which the gas or vapor is generated is also admitted at the same point by means of a pipe 12, one end of which opens into the hollow shaft 5, and the other is connected with an open-topped tank 13. This tank 13 is connected by a pipe 14 with a larger closed tank 15. The object of this connection is to supply the liquid from the larger tank 15 into the smaller tank 13 by gravitation and displacement—that is, whenever the liquid in the tank 13 falls below the level of the connecting pipe or passage 14 a little air will pass through this pipe into the tank 15 and rising to the top will displace a portion of the liquid, which thus passes by gravitation into the tank 13. This maintains the level of the liquid in tank 13 at a point just below the upward curve 16 of the connecting-pipe, so that when the engine is not running this upward curve serves as a trap to prevent any liquid flowing into the generator.

Whenever the engine is running, the suction caused by the piston produces a vacuum and acts to draw the vapor from the cylinder 4 into the engine through the pipe 9 and valve 8, and the vacuum thus produced within the cylinder 4 causes an inrush of air through the valve-controlled passage 11; but this passage is purposely made too small to supply all the air needed, and the vacuum will thus act partially to draw the liquid in through the connecting-pipe from the tank 13, the pressure of air in tank 13 being sufficient to force a little of the liquid over the trap 16 at each stroke of the engine when gas is being drawn into it.

The generator 4 is rotated slowly by means of any suitable gear or pulley connection with the main shaft of the engine, the rate of speed being determined and the parts proportioned as desired.

The connection between the hollow shaft or trunnion 10 and the suction-pipe 9 may be made by a suitably-packed revoluble joint 18.

Under ordinary conditions the exhaust-valve 19 is opened by the pressure of a tilting lever 20, centrally fulcrumed, having one end with an adjustable tappet 21, adapted to contact with the lower end of the stem 22 of the valve. The opposite end of the lever 20 has an antifrictional roller journaled in it, and this is in line with a cam 23, which is mounted upon a shaft 24, suitably connected and revoluble from the engine-shaft, so that as the cam revolves it tilts the lever 20 and raises the valve-stem 22 at each reciprocation of the engine-piston, so as to allow the products of combustion to escape when the piston returns toward the rear end of the cylinder.

When the speed of the engine is so great that it is not desired to produce an explosion for one or more revolutions, the exhaust-valve is kept open by the action of the governor, (not here shown,) which by means of the lever-arm 25 or equivalent connection acts to lift the valve-stem 22 and hold the exhaust-valve open for one or more strokes or until the engine and governor are running slow enough to again allow the valve to close. When the exhaust-valve is thus opened, the movement of the piston will simply draw in air through this valve and force it out again, but will not draw any explosive gas from the generator. As no vacuum will be produced in the generator during the time while the exhaust-valve thus remains open, it will be seen that no liquid will be drawn in from the supply-tanks. Thus the supply of liquid to the generator is very exactly proportioned to the needs of the engine, which is an important consideration.

The supply of gas from the generator may be manually regulated by means of a cock 26, and the final supply of air to mix with the gas as it enters the cylinder is regulated by means of a cock 27.

In order to ignite each charge which enters the cylinder, I have shown an igniter or sparking device, which consists of contact-points 28 and 29, the ends of which are adapted to oscillate past each other and make and break contacts when each charge of gas has been properly compressed in the engine-cylinder. The arm carrying the contact-point 28 projects from a journal-shaft 30, and the arm carrying the contact-point 29 is mounted upon a shaft 31, which projects through the igniting-chamber and has upon its outer end a transverse arm 32. This arm is alternately rocked or oscillated to one side and the other by means of arms 33, projecting in opposite directions from the shaft 24, which also carries the exhaust-valve-actuating cam 23, as previously described. The revolution of this shaft 24 alternately brings one of the arms 33 into contact with the transverse arm 32, and as this contact takes place upon opposite sides of the shaft 31 the arm 32 will be oscillated,

and with it the shaft 31 and the contact-point 29. This causes this contact-point 29 to brush past the point 28, the latter turning or oscillating sufficiently to allow the point 29 to pass, and this turns the shaft 30, which has upon it a projecting lug 34. This lug enters between the two leaves of a spring 35, and this spring yields whenever the points 29 and 28 pass each other; but as soon as 29 has passed 28 the action of the spring 35 upon the lug 34 will immediately return the arm 28 to its normal position, and this makes a sudden break between the two contact-points and produces a spark which is sufficient to explode the charge of gas within the cylinder.

The cylindrical generator 4 has the end with which the discharge connects made of larger diameter, so as to form an annular channel 37, and into this channel any residue from the hydrocarbon liquid which remains after all the gas or volatile products have been removed by the heat will be delivered. In order to remove this residue and prevent its accumulation in the generator, I have shown a spirally disposed or coiled pipe 38, the outer end of which extends into the channel 37, so that as the cylinder and coiled pipe revolve this end will at each revolution dip up any liquid which may have settled into this channel and will convey it to the center, where the pipe discharges outwardly through a discharge-pipe 39.

Having thus described my invention, what I claim as new, and desire to secure by Letters Patent, is—

1. The combination with an explosive-engine and the pumping and propelling piston thereof, of a horizontally-disposed rotating cylinder with interior spiral ribs, and means for supplying hydrocarbon liquid thereto, an exterior casing surrounding said cylinder having inlet and discharge passages and connection between the exhaust of the engine and the inlet-passage of said casing.

2. In an explosive-engine, a generator comprising an exterior horizontally-disposed casing with inlet and outlet passages and connections by which the exhaust products from the cylinder are discharged thereunto, a cylinder journaled and revoluble within said casing having spirally-disposed ribs or flanges extending from end to end, means for supplying hydrocarbon liquid at one end of the cylinder, and a tubular connection between the opposite end of the cylinder and the inlet-valve of the engine.

3. In an explosive-engine, a horizontally-journaled revoluble cylinder having spirally-disposed interior flanges, an exterior inclosing casing through which the hot products of combustion from the engine are discharged, a hollow journal-shaft at one end and pipe connection with the inlet-valve of the engine, a hollow journal at the opposite end, an opening through which air is admitted into the generator during the operation of the engine.

4. In an explosive-engine, a horizontally-

5 journaled revoluble cylinder with spirally-arranged interior flanges, a stationary jacket through which heat from the exhaust products of the engine is applied, a hollow journal at one end and pipe connection with the inlet-valve of the engine, a similar journal at the opposite end, with valve-controlled air-inlet opening and a pipe through which the hydrocarbon liquid is also admitted thereto.

10 5. In an explosive-engine, a horizontally-journaled revoluble cylinder, with means for advancing the liquid therethrough, an exterior stationary jacket through which the hot exhaust products from the engine are discharged, a hollow journal at one end of the generator and pipe connection with the inlet-valve of the engine, a similar hollow journal with controlling-valve through which air is admitted into the generator by the vacuum

15 produced by the engine, supply-tanks and pipe connection with said inlet-passage whereby the hydrocarbon liquid is also admitted simultaneously.

20 6. In an explosive-engine, the horizontally-revoluble cylindrical generator with interior spirally-disposed flanges by which the liquid is advanced from the inlet toward the discharge end, a channel at the discharge end of larger diameter and a coiled pipe, the outer

25 30 end of which dips into the lower part of said channel whereby the residue is constantly collected therefrom.

7. In an explosive-engine, a horizontally-

journaled revoluble cylinder with means for advancing the hydrocarbon liquid therethrough, means for heating the generator to vaporize the liquid, a pipe connection from one end of the generator to the inlet-valve of the engine, a closed main tank and an open-topped supplemental supply-tank with connection between, and upwardly-curved trap-pipe connecting the supplemental chamber with the inlet end of the generator whereby the vacuum produced by the engine-piston acts to draw the liquid into the generator. 35

40 8. In an explosive-engine, a horizontally-journaled revoluble generator, with means for advancing the liquid therethrough, and means for heating the same, an open-pipe connection between the discharge end of the generator and the inlet-valve of the engine whereby a vacuum is produced in the generator by the movement of the engine-piston, a pipe-and-trap connection between the opposite end of the cylinder and the supply-tank whereby the hydrocarbon liquid is drawn into the generator when the engine-piston produces a vacuum and the supply is cut off when the inlet-valve of the engine has not opened or the engine is at rest. 45 50 55 60

In witness whereof I have hereunto set my hand.

HENRY L. JESSEN.
